UNITED STATES PATENT OFFICE.

BERNARD C. MARGILETH, OF AURORA, INDIANA.

FIRE-PROOF BOX FOR FIRE-ESCAPES.

SPECIFICATION forming part of Letters Patent No. 289,287, dated November 27, 1883.

Application filed September 13, 1883. (No model.)

To all whom it may concern:

Be it known that I, BERNARD C. MARGILETH, a citizen of the United States of America, residing at Aurora, in the county of Dearborn and State of Indiana, have invented certain new and useful Improvements in Fire-Proof Boxes for Fire-Escapes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to fire-escapes; and it consists of an improved device, fully described hereinafter, whereby persons, goods, &c., may be safely and readily lowered from various heights without subjecting the same to jar or

20 shock.

In the accompanying drawings, Figure 1 is a perspective view of my improved device, the doors being open to reveal the interior. Fig. 2 is another perspective view, showing the device out of operation and arranged for stowage or transportation; and Fig. 3 is a view of the under side of the device.

25 A B represent metallic bars, curved at their ends to form bearings a for the ends of journals b, upon which turn rollers c, located in notches d, formed in the ends of said bars. The bars A B form the sides, and transverse bars C D, respectively, the top and bottom, of a frame, the said bars C D being connected to the bars A B at their ends on the rear sides of said bars. Upon the described metallic frame is riveted or otherwise secured a leather backing, E. Transverse wooden bars F G, connected at their ends to the side bars, A B, by

30 any suitable devices at about the same points as the bars C D, but on the front side of the bars A B, have respectively hinged thereto the rear straight edge of the semicircular sections f g, forming, respectively, the top and bottom of the receptacle proper, which sections f g are normally at right angles to the back E, but can be readily folded back to occupy a plane parallel therewith, as shown in Fig. 2.

35 To the front side of the bar A is hinged a curved section, H, which rests between the top f and bottom g, and forms one half of the

front portion of the receptacle proper, while a second curved section, I, similar to the section H, is hinged thereto, and constitutes the 55 remaining portion of the front of the receptacle proper. The sections H and I are made of flexible fire-proof material—as leather treated with a fire-proof composition, thin plates of steel or iron, or of a fabric manufactured and 60 treated for this purpose. A cord, h, attached to the edge of the section I, as seen in Fig. 1, passes through a staple, i, secured to the bar B, and carries a counterpoise or weight, j, at its end, so as to normally hold the sections H 65 I closed between the top f and bottom g, and hence close the receptacle proper. Hooks k l, pivotally secured to one of the ends of the bars F G, are adapted to engage staples m n on the outer side of the section I, near the edge thereof, and thus rigidly retain the sections H I in a closed position.

Beneath the bottom g and to the bars A B are pivotally hinged brackets J K, the ends of vertical bars o of the said brackets being swiv- 75 eled in loops p, secured to the bars A B. The said brackets J K carry at their outer ends vertical pins q, which, when the brackets are in the position illustrated in full lines, Fig. 3, bear in eccentric grooves r and support said 80 bottom, but when in the position illustrated by dotted lines permit the bottom to be turned down parallel with the back E, as previously described. Rods L M, extending parallel with and projecting from the ends of the bars A B, 85 beneath the bottom g, are cylindrical at their ends, to receive elastic or spring buffers N.

A T-head, O, is bolted centrally to the bar C. The hoisting and lowering rope having been passed around and secured to the T-head 90 O, the front sections are secured by having the section I rigidly hooked to the bar B, and the brackets being in the position shown in Fig. 1, the top f is thrown back, thus enabling articles to be placed within the receptacle 95 formed by the bottom g, backing E, and front sections, H I, to be lowered, which can be effected without difficulty by reason of the rollers c bearing against the front of the building.

Any tendency to jar the contents as the device comes in contact with the ground will be overcome by reason of the elastic or spring buffers N, which can be removed, and the extension-rods L M utilized as handles to raise

the rear end of the device and wheel it off on its front wheels in the manner of the ordinary wheelbarrow.

When the device is not in use, the brackets 5 can be turned down to the position shown in dotted lines, Fig. 3, the bottom and top folded back parallel with the back E, and the front sections folded down in the position shown in Fig. 2, by which arrangement the entire device 10 occupies the minimum space for stowage or transportation.

The back E, top f, front sections, H I, and top covering of the bottom may be made of any desired material, preferably non-combustible; hence I do not limit myself to the use of leather.

The grooves in the bottom section may be omitted, in which event the bottom section will be hinged to fall in different directions, 20 and will be provided with holes for the reception and retention of the pins q of the brackets. The counterpoise and cord maintain the front sections closed when they are not secured by the hooks.

25 I claim—

1. The combination, in a box or car designed for use in connection with fire-escapes, with a metallic frame forming the back of a recep-

tacle or chamber, and having rollers located at its ends, of the front portion consisting of 30 hinged sections H I, substantially as set forth.

2. In a box or car designed for use in connection with fire-escapes, a receptacle consisting of hinged top and bottom sections and of hinged front sections, substantially as and 35 for the purpose set forth.

3. In a box or car designed for use in connection with fire-escapes, a receptacle consisting of hinged top and bottom sections and of hinged front side sections, the bottom section 40 being grooved on its under side to receive the projecting pins of swiveled brackets bearing on the frame beneath, substantially as set forth.

4. In a box or car designed for use in connection with fire-escapes, a receptacle 45 provided with hinged front sections, H I, adapted to be normally maintained closed by a cord and counterpoise, substantially as set forth.

In testimony whereof I affix my signature in 50 presence of two witnesses.

BERNARD C. MARGILETH.
